UNITED STATES PATENT OFFICE.

HENRY J. TRAH, OF CHICAGO, ILLINOIS.

HAT-BRUSH.

1,077,654.

Specification of Letters Patent.

Patented Nov. 4, 1913.

Application filed March 28, 1913. Serial No. 757,343.

To all whom it may concern:

Be it known that I, HENRY J. TRAH, a citizen of the United States, and a resident of the city of Chicago, county of Cook, and

5 State of Illinois, have invented certain new and useful Improvements in Hat-Brushes, of which the following is a specification.

My invention relates to hat brushes and more specifically to that class thereof de-10 signed for carriage in the hat.

The object of my invention is the production of a hat brush as mentioned which will be of durable and economical construction and efficient in use.

15 Other objects will appear hereinafter.

The invention consists in the combinations and arrangements of parts hereinafter described and claimed.

20 The invention will be best understood by reference to the accompanying drawing forming a part of this specification, and in which—

25 Figure 1 is a vertical section of a hat in which is arranged a brush embodying my invention, Fig. 2 is a side elevation of the brush detached, Fig. 3 is a section taken on line $x-x$ of Fig. 2, Fig. 4 is a detail section taken on line $y-y$ of Fig. 2, and Fig. 5 is a plan view of the blank from which the 30 back of the brush is formed.

The preferred form of construction as illustrated in the drawing comprises bristles 1 which are arranged in a thin plane at one edge of a thin flat handle 2. Said bristles 35 are connected with said edge of said handle through the medium of a back which, in the construction of the brush, is formed of a blank 3 of sheet metal in a single piece, as clearly shown in Fig. 5. The blank 3, in 40 the formation of the back therefrom, is bent upon a center line 4, to form an elongated narrow recess 5 adapted for the reception of the adjacent ends of the bristles 1, the sides of said recess, in the formation of the brush, 45 being pressed into secure engagement with said bristles.

In order to engage the adjacent edge of the handle 2, the longitudinal edges of the blank 3 are bent back on lines 6 in order 50 to form elongated narrow recesses 7, as clearly shown in Fig. 3. The lower edge of the handle 2, in order to engage the recesses 7, is bifurcated, the branches or leaves snugly engaging said recesses as shown in 55 said Fig. 3. The handle 2, in use, is either formed of two sections which are glued or

otherwise fastened as shown or said handle may be formed of a single piece and the lower edge thereof slotted in effecting bifurcation thereof.

60

In the construction of the brush, in order to effect a secure and rigid fastening of the bristles and handle in the back, the ends of said bristles and the edge of said handle are preferably glued in position in addition to 65 being clamped in the manner shown. Provided at the ends of the blank 3 are ears 8 which, when said bristles and handle are secured in position in the back as mentioned, are bent around the respective extremities 70 of the back in order to finish off the same, thereby conducting to a neat and finished construction as well as to firmness and rigidity.

A brush of the construction set forth is 75 simple and economical in construction and hence may be manufactured at a low cost, the same is also exceptionally light in order to adapt the same for carriage in the hat, in which carriage thereof the handle 2 is inserted to position behind the sweat band 80 of the hat, as shown in Fig. 1. The handle 2, by reason of the shape and dimensions thereof, presents considerable surface which may be utilized for advertising if desired.

While I have illustrated and described the 85 preferred form of construction for carrying my invention into effect, this is capable of variation and modification without departing from the spirit of the invention. I, therefore, do not wish to be limited to the 90 precise details of construction set forth, but desire to avail myself of such variations and modifications as come within the scope of the appended claims.

Having described my invention what I 95 claim as new and desire to secure by Letters Patent is:

1. A brush comprising bristles; a handle; means for securing said bristles to said handle; said means comprising a member 100 having a recess in one side for the reception of the ends of said bristles; and a recess in its opposite side for the reception of one edge of said handle, substantially as described.

105

2. A brush comprising bristles; a handle; means for securing said bristles to said handle, said means comprising a member having a recess in one side for the reception of the ends of said bristles; and two recesses 110 at its opposite side for the reception of one edge of said handle, said edge of said han-

dle being bifurcated to engage said last mentioned recesses, substantially as described.

3. A brush comprising bristles; a handle; a back establishing connection between said bristles and said handle, said back being formed of a single piece of sheet metal bent upon itself to form an elongated narrow recess for the reception of the ends of said bristles; and oppositely opening elongated narrow recesses at the opposite sides of said first mentioned recesses for the reception of one edge of said handle, said edge of said handle being bifurcated to engage said last mentioned recesses, substantially as described.

4. A brush comprising bristles; a handle; a back establishing connection between said bristles and said handle, said back being formed of a single piece of sheet metal bent upon itself to form a recess in one side for the reception of the ends of said bristles; oppositely opening recesses for the recep-

tion of one side of said handle; and ears on said back-forming piece folded to embrace the ends of said back, substantially as described.

5. A brush comprising bristles; a handle; a back establishing connection between said bristles and said handle; said back being formed of a single piece of sheet metal bent upon itself to form a recess in one side for the reception of the ends of said bristles; oppositely opening recesses for the reception of one side of said handle; and ears at the ends of said back-forming piece engaging around the end of said back, substantially as described.

In testimony whereof I have signed my name to this specification in the presence of two subscribing witnesses.

HENRY J. TRAH.
